WEATHER SHIELD FOR A NEWSPAPER BOX
Howard C. Ross, Acorn Farm, Gainesville, Va.
Filed Oct. 10, 1962, Ser. No. 229,528
3 Claims. (Cl. 232—17)

The present invention relates to newspaper boxes as employed in rural areas for the temporary storage of home delivered newspapers.

Presently in use in rural areas are open ended boxes, fabricated of relatively stiff metal and supported upon the upper ends of posts driven into the ground. Generally these boxes are provided by the newspaper publishing company and are available to the rural home owner for use by the local newspaper delivery person.

Generally such boxes are open ended and have one or both ends exposed to the elements. Each box is of a size to accommodate a rolled up newspaper but are not of a size to permit the insertion of such a newspaper into the box a depth necessary to protect the end of the newspaper from the elements.

An object of the present invention therefore is to provide a weather shield for a newspaper box of the type employed in rural areas for the temporary storage of a home delivered newspaper, one which lends itself to attachment to such a box with ease and facility, one which may be manufactured in quantity at reasonable cost, and one which is highly effective in action.

Another object of the present invention is to provide a weather shield for a newspaper box of the type employed for the temporary storage of a newspaper in rural areas which is sturdy in construction, one having few parts readily and with facility assembled, and one which is transparent so that the contents of the box may be viewed through the shield.

These and other objects and advantages of the present invention will be fully apparent from the following description when taken in connection with the annexed drawing, in which:

FIGURE 1 is a perspective view of the shield of the present invention installed upon one end portion of a newspaper box, the box being broken away and the post supporting the box having its lower portion broken away,

FIGURE 2 is a view in section of the portion of the assembly shown in FIGURE 1, and

FIGURE 3 is an elevational view of the assembly shown in FIGURE 1.

With reference to the drawing in detail, in which like numerals indicate like parts throughout the several views, the reference numeral 10 designates generally an open ended box fabricated of sheet metal or the like of the type which is generally employed by newspaper publishing companies for the temporary storage of newspapers as delivered by a newspaper carrier in a rural area.

The weather shield of the present invention consists in an inverted U-shaped tunnel member 12 having legs 14 and 16, and a bight 18 connecting the upper ends of the legs 14 and 16 together.

A portion of the tunnel member 12 adjacent one end embracingly engages the one end portion of the box 10 adjacent the open end thereof.

Between the legs 14 and 16 and dependingly secured to the bight 18 is a flexible gate 20 disposed intermediate the ends of the tunnel member 12 and relative to the tunnel member 12 so that it may swing into and out of the open end of the box 10 freely as shown in dotted lines in FIGURE 2.

The gate 20 and its support, a tab 22, is formed integrally and the junction of which constitutes a fulcrum support axis, with the tab 22 cemented to the underside of the bight 18 as shown most clearly in FIGURE 2.

2

Preferably, the tunnel member 12 is fabricated of a resilient transparent material such as plastic and fabricated so that the portion adjacent one end embracingly engages the portion of the box adjacent one of the open ends thereof.

It will be seen that the gate 20 substantially closes the open end of the box 10 and is free of the open end of the box 10 so that a person inserting a newspaper into the box 10 may lift up the gate 20 a distance sufficient to pass the newspaper thereunder.

Conventionally, the box 10 is supported on the upper end portion of a post 24 by means of a clamp mechanism 26. Such construction is usual and no claim for the same is made in this application.

While only a preferred embodiment of the present invention is shown and described, other embodiments of the invention are contemplated and numerous changes and modifications may be made in the invention without departing from the spirit thereof as set forth in the appended claims.

What is claimed is.

1. A detachable weather shield accessory for use with an open-ended, generally horizontally disposed, rural delivery newspaper or mail tube, comprising:

(a) a snap-on, inverted U-shaped, tunnel member having open ends, which is

(1) fabricated of a resilient but fairly rigid material, and

(2) adapted to be readily attached to or removed from the open end of said tube by resilient snap-on or snap-off action respectively of the resilient member:

(b) said tunnel member comprising an upper portion of a generally horizontally disposed bight member interconnected with a pair of opposed, spaced apart resilient side leg members which are dependently supported from said bight member:

(c) a freely swingable, single closure gate panel of a size slightly smaller than the open end area of said tube and having an upper and lower edge: and

(d) said gate having a generally horizontal fulcrum support axis near its upper edge and being swingably and dependently supported thereat from the upper portion and intermediate the ends of the said tunnel member.

2. A detachable weather shield accessory as defined in claim 1, wherein:

said gate panel is disposed to be maintained by gravity in a normally vertical plane transversely of but in a substantial spaced apart relation to the lower portion of the open end of said tube, thereby facilitating a free grasp of the lower edge of said gate to open same for insertion of a newspaper or mail therewith into said tube.

3. A detachable weather shield accessory as defined in claim 1 which:

(a) is fabricated of a relatively lightweight, durable, resilient sheet material including plastic and metallic alloy compositions: and

(b) wherein the gate panel is made of transparent sheet material.
